GEORGE WILLIAM BERRY, OF ROSE BAY, NEW SOUTH WALES, AUSTRALIA, ASSIGNOR
TO THE WIRELESS HINGE MANUFACTURING COMPANY LIMITED, OF SYDNEY, NEW
SOUTH WALES, AUSTRALIA.

HINGING OF SHEET-METAL RECEPTACLES.

1,317,421.

Specification of Letters Patent. Patented Sept. 30, 1919.

Application filed May 11, 1917, Serial No. 167,941. Renewed May 29, 1919. Serial No. 300,786.

To all whom it may concern:

Be it known that I, GEORGE WILLIAM BERRY, a subject of the King of Great Britain, residing at Lorna Doone, Old South Head Road, Rose Bay, in the State of New South Wales, Commonwealth of Australia, have invented certain new and useful Improvements in the Hinging of Sheet-Metal Receptacles, of which the following is a

specification.

This invention relates to improvements in the manufacture of hinges for hingedly connecting lids to receptacles, and it has been devised particularly in order to provide means whereby hinge members can be formed on the lid and body of a sheet metal receptacle and the like and pivotally connected without the aid of the short piece of wire ordinarily employed for the purpose.

The hinge is formed entirely out of the material of the lid and body of a receptacle and is made by passing the said lid and body successively within the sphere of operation of two or more sets of shaping dies and a closing die.

The invention comprises also improvements in the formation of the hinge members whereby the hinging operation will be simply and economically performed in a highly efficient manner and a strong and durable hinge will result.

In order that the invention may be readily understood reference will now be had to the accompanying drawings wherein

Figure 1 is a perspective view showing a lid and body having hinge members formed thereon constructed in accordance with the present invention.

Fig. 2 is a perspective view showing the lid and body hingedly connected by said members.

Fig. 3 is a perspective view drawn to an enlarged scale showing one of the hinges formed by the members shown in Fig. 1.

Fig. 4 is a view in sectional side elevation taken on the plane 15—15 of Fig. 3.

Fig. 5 is a perspective view of portions of a lid and a body showing a modification of the method of hingedly connecting the lid and body of receptacles; and

Fig. 6 is a perspective view showing the lid and body hingedly connected by the members shown in Fig. 5.

In the drawings like characters of refer-

ence have been employed to indicate similar or corresponding parts in the different views and the numeral 1 designates a lid the rim 2 of which is formed of greater depth at the back than the front and ends thereof.

The depending portion of the back of the lid is creased or folded longitudinally into a crease substantially of U-shape in cross section by means of dies. When the crease 3 has been formed on the back of the lid 1 slots or perforations are cut at any intermediate points in the backs of the lids directly above the crease 3. Arches positioned to aline or coincide with the slots 17 in the lid are pressed in the backs of the bodies 7; the backs of the bodies are pressed slightly inward to substantially semi-circular shape in cross section as shown at 10, said depression 10 being in line with the arches and extending from outside one arch to a point outside the other arch. This depression is preferably formed by the same dies and simultaneously with the forming of the arches, the material at the juncture of said arches and depression 10 being slotted transversely. After the arches are formed the material is slotted at the top of the arches and the outer side, and the arched portion of the back pressed out forming arched tongues 18, as clearly shown in Fig. 1.

To hingedly connect lids and bodies formed with hinge members as above described the bodies are placed over one side of a die and the lids are passed over the opposite side of the die with perforations 17 directly beneath the tongues 18. With the lids and bodies in this position the top member of the die descends and presses the tongues 18 back to their original positions with the arched portions engaging over the creased portion 3, as shown in Fig. 4. To prevent the escape of any fine substance, such as powder or the like, which may be packed in the receptacles the ends of the crease 3 are "blinded" or closed as shown in Fig. 3 and engage in the recessed portion 10 formed at the outer sides of the tongues.

As shown in Figs. 1 and 2 a pair of arched tongues 18 are provided to coöperate with the slots 17 above the crease 3 to hingedly connect the lids and bodies. However, if desired a plurality of such tongues may be provided, as shown in Figs. 5 and 6. As shown in said figures the slots which are

provided above and at the ends of the crease 3 are cut through the edge of the rim of the lid, as shown at 4, thereby forming pintles at the end of the creased portion 3. The 5 arches of the end tongues may be formed with outer side walls to close the outer ends thereby forming the arches of the outer tongues or at the end in the form of bulbs, as clearly shown in said figures with the de- 10 pression 10 extending only to the inner end of the outer tongues, whereby as said tongues are pressed back to engage the free ends of the crease formed by the slots 4 they will serve to close and seal the ends of the crease 15 and thereby prevent leakage of the contents of receptacles.

What I do claim is:—

1. In a metal box, comprising a lid and body, the lid having a rim with a depending 20 part of convex and substantially semi-circular form and provided with spaced recesses above and at the ends of said portion, and the body having spaced arched tongues of convex and substantially semi-circular form 25 with their free ends extended from said convex bends, the portion of the body intermediate and at the outer ends of the tongues being depressed into concave and substantially semi-circular form in which concave 30 portion the convex portion of the lid rim is adapted to movably engage and the convex

portion of the tongues engaging over said depending convex portion of the lid rim with the extended ends of the tongues engaging in the recesses above and at the ends of the 35 convex portion of the lid rim, and said hinged connection arranged at the ends to close the openings formed by the convex and concave portions of the hinged connection.

2. In a metal box, a box body having 40 spaced arched tongues of convex and substantially semi-circular form with their free ends extended from said convex bends, the portion of the body intermediate the tongues being depressed into concave and substantially semi-circular form and a lid for the body having a part of convex and substantially semi-circular form and provided with spaced perforations above said part normally receiving the extended free ends of 45 the tongues, one section of the hinged connection that is relatively movable to the body having closed ends for closing the opening formed by said convex and concave portions of said hinged connection.

In witness whereof I have signed this specification in the presence of two witnesses.

GEORGE WILLIAM BERRY.
